(74) *Attorney, Agent, or Firm*—Michael Best & Friedrich LLP

(21) Appl. No.: **29/123,048**

CLAIM

(22) Filed: **May 5, 2000**

The ornamental design for a skillet, as shown and described.

(51) **LOC (7) Cl. 07-02**
(52) **U.S. Cl. D7/360**
(58) **Field of Search D7/323, 354-360,**
D7/393; 219/620-622; 99/324, 325, 339

DESCRIPTION

(56) **References Cited**

FIG. 1 is a perspective view of a skillet constructed in accordance with one preferred embodiment of the invention; FIG. 2 is a top plan view of the skillet shown in FIG. 1; FIG. 3 is an elevation view of the front of the skillet shown in FIGS. 1 and 2 (the rear of the skillet being a mirror image of the front);

FIG. 4 is an elevation view of the right of the skillet shown in FIGS. 1, 2 and 3;

FIG. 5 is an elevation view of the left of the skillet shown in FIGS. 1, 2, 3 and 4; and,

FIG. 6 is a bottom plan view of the skillet shown in FIGS. 1, 2, 3, 4 and 5.

The broken lines shown in FIGS. 1-6 are for illustrative purposes only and form no part of the claimed design.
